Atty's

UNITED STATES PATENT OFFICE.

RICHARD SZEKERES, OF MAGYAROVAR, HUNGARY.

MATCH BOX.

Application filed November 2, 1925, Serial No. 66,388, and in Germany July 22, 1924.

The present invention refers generally to improvements in illumination and more particularly relates to a cigar lighter.

The invention as its primary aim and object contemplates the provision of a lighter of the above character constructed to resemble a cartridge shell of two parts one part of which receives a container for the liquid and ignition means while the other part acts as a closure.

As an additional and equally important object the invention resides in the provision of an igniter of the above character wherein ignition means of improved construction is mounted on both of the parts of the shell-like casing so that when one part is moved relative to the other a spark is produced for effecting an ignition of the wick.

Other objects as well as the nature, characteristic features and scope of the invention will be more readily apparent from the following description taken in connection with the drawings and pointed out in the claim.

The invention is clearly illustrated in the accompanying drawings, in which:—

Fig. 1 is a side elevational view partly in section showing one form of the invention, and

Fig. 2 is a side elevational view showing another form, the parts being shown in extended position.

Similar characters of references are employed in all of the above described views to indicate corresponding parts.

Referring now, more particularly, to the accompanying drawings there is provided a shell-like casing including a cap-like section or part *a* having a reduced portion *b* said section or part receiving a fuel receptacle *c* the latter being fitted with a wick *e* and igniter *f* while the other part *g* of the casing is constructed to simulate a charge containing portion of a shell but in reality acts as a closure for removable engagement with the reduced portion *b* of the part *a*. In use it is only necessary to remove the part *g* and turn the wheel of the igniter *f* to produce a spark to ignite the wick *e*. Subsequently a replacement of the part *g* serves to extinguish the wick when the device is in con-

dition for being carried in the pocket or like of the user.

In Fig. 2 the cap-like section *a'* acts as a closure for the section *g'* which is constructed to simulate a charge receiving portion of a shell and has the inner end reduced as at *b'* and constructed hollow to receive the fuel container *c'* in turn fitted with a wick *e'*.

With a view toward providing the improved spark reducing means an arm *h'* is carried with one edge of the flanged portion of the cap part *a* being preferably integral therewith and provided on its inner surface with serrations. This part *h'* is slidably accommodated within the part *g'* and the container *c'* preferably in a suitable guideway *k'* while suitably mounted through a passageway *l'* in the container *c'* is a spark reducing element *n'* which may be for instance formed of pyrophoric material. The element *m* is yieldingly held at one end of the passageway *l'* and in yielding contact with the serrated surface of the arm *h'* by suitable expansion means such as a coiled spring *n*'. When using this form of the invention it will be apparent that upon the raising of the cap *b'* sliding frictional contact between the serrated surface of the arm *h'* and the spark reducing element *m*' a spark is produced to ignite the wick *e*. Subsequently the spark is extinguished upon the pressing of the cap.

It is believed in view of the foregoing that a further detailed description of the operation of the invention is entirely unnecessary. Likewise it is believed that the advantages of the invention will be readily apparent.

Having thus fully described the invention what is claimed as new and desired to be secured by Letters Patent is:—

A cigar lighter of the character described, including a casing resembling a cartridge shell and constructed in two parts, a fuel container mounted in one of said parts and projecting outwardly therefrom and provided with a transverse passageway, a wick in the fuel container, the other part acting as a cover, a serrated arm extending from the cover part and slidably received between

the inner wall of the other part and the outer wall of the container, a spark producing element slidably and resiliently mounted in the passageway and yieldingly contacting the casing being removably engaged about the container when in a closed contacting position with respect to the other part of 10 the casing.

5 with the serrated portion of the arm so that when the cover part and arm are withdrawn a spark is produced, and the cover part of

In testimony whereof I have signed my name to this specification.

RICHARD SZEKERES.
